PAIR OF SPECTACLES

Donald J. McCulloch, Greece, N.Y., assignor to Bausch & Lomb Incorporated, Rochester, N.Y., a corporation of New York

Filed May 17, 1965, Ser. No. 85,324

Term of patent 14 years

(Cl. D57—1)

FIG. 1 is a front view of a pair of spectacles showing my new design;

FIG. 2 is a top view thereof;

FIG. 3 is a side view of said spectacles taken from the left side thereof as viewed in FIG. 1;

FIG. 4 is a sectional view taken along the line 4—4 in FIG. 3 and looking in the direction of the arrows; and

FIG. 5 is a sectional view taken along the line 5—5 in FIG. 3 and looking in the direction of the arrows.

The side not shown has substantially the same appearance as the side shown.

My design for the spectacles disclosed is characterized by the chamfered top portion of the spectacle frame as shown.

I claim:

The ornamental design for a pair of spectacles, substantially as shown and described.
